UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,479, dated September 20, 1881.

Application filed August 9, 1881. Term of patent 3½ years.

To all whom it may concern:

Be it known that I, HENRY HORAN, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A large bouquet, A, of roses and other flow-

ers, surrounded by radiating fern-leaves a, is placed on a background, B, which is entirely covered with leaves and flowers ranged in an apparently inextricable mass.

I claim—

The design for carpets, consisting of the bouquet A, having leaves a, and of the background B, substantially as shown.

HENRY HORAN.
